(57) CLAIM

The ornamental design for an inflatable umbrella, as shown and described.

DESCRIPTION

FIG. 1 is a perspective view of the claimed design.

FIG. 2 is a side view of the claimed design.

FIG. 3 is another side view of the claimed design; and,

FIG. 4 is a bottom view of the claimed design.

The broken lines are shown for the purpose of illustrating unclaimed portions of the inflatable umbrella and form no part of the claimed design.

1 Claim, 4 Drawing Sheets

FIG. 1

FIG. 4
